C. E. SMITH,
IGNITION MEANS FOR GAS BURNERS,
APPLICATION FILED APR. 30, 1914.

1,173,052.

Patented Feb. 22, 1916.

UNITED STATES PATENT OFFICE.

CHARLES ERNEST SMITH, OF VERNON, BRITISH COLUMBIA, CANADA, ASSIGNOR OF
ONE-HALF TO HAMILTON LANG, OF VERNON, BRITISH COLUMBIA, CANADA.

IGNITION MEANS FOR GAS-BURNERS.

1,173,052.

Specification of Letters Patent.

Patented Feb. 22, 1916.

Application filed April 30, 1914. Serial No. 835,578.

To all whom it may concern:

Be it known that I, CHARLES ERNEST SMITH, a citizen of the Dominion of Canada, residing at Vernon, British Columbia, 5 Canada, have invented certain new and useful Improvements in Ignition Means for Gas-Burners, of which the following is a specification.

In the present invention the object in 10 view is to provide novel means for igniting the gas lamps of a motor vehicle through the instrumentality of the high tension current which is customarily delivered to the engine of said vehicle.

15 In carrying out the invention it is contemplated to employ a switch member interposed in the circuit conducting the current to the usual sparking element or plug of the engine, in combination with operating 20 means normally maintaining the circuit complete to said plug and operable to momentarily direct the current to sparking electrodes at the gas lamps for igniting the gas.

A further object of the invention is to provide 25 gas distributing means whereby to supply the lights and enable independent control thereover to permit them to be operated separately or in combination.

These and such other objects as may here- 30 inafter appear are attained by the novel construction, combination and arrangement of parts to be hereinafter described and claimed.

Reference will now be made to the drawing 35 forming a part of this specification wherein:—

Figure 1 is a fragmentary side elevation of a motor vehicle to which my invention is applied, certain parts being shown in section, and Fig. 2 is a diagrammatic view 40 showing more clearly the arrangement of electric circuits and gas distributing conduits.

Throughout the following detail descrip- 45 tion, and on the several figures of the drawings, similar parts are referred to by like reference characters.

Specifically describing the invention and referring to the drawing, the numeral 1 designates an internal combustion engine of 50 the customary type disposed in proper relation to the dash 2 of a motor vehicle, and 3 designates the usual form of source of

electric current or magneto designed to supply to the explosive engine an electric current 55 for sparking purposes, passing through the conductors 4 to the spark plugs of each cylinder.

The numeral 5 designates a suitable form of gas container for supplying gas to the 60 burners 6 of the lamps of the vehicle and the gas from the tank 5 is conducted to the forward burners through the conduit 7 and to the burner of the rear lamp through the conduit 8, said conduits leading to a gas 65 distributer 9 arranged at any convenient point on the vehicle, such as on the dashboard, readily accessible to the operator of the vehicle, to which distributer the gas from the tank 5 passes through the conduit 70 10. The distributer 9 is provided with the main valve 11 and independent auxiliary valves 12, 12'.

Arranged on the motor or at any other suitable point of the vehicle is a switch 13 75 which switch is interposed in one of the circuits leading to a cylinder of the engine 1 and also connected to this switch is a conductor 14 leading first to the burners of the front lamps and passing to the burner of the 80 rear lamp from which it is grounded to the engine, all as clearly shown in Fig. 2 of the drawing. At each of the burners, as shown most clearly in Fig. 1, is arranged a spark 85 gap 15 by means of which gas issuing from said burners may be ignited when the current from the magneto 3 is directed through the conductor 4 with which the electrodes 15' are connected at one end to the switch 13.

At 16 is designated an operating member 90 or rod which is connected at one end to the switch 13 while its other end is disposed at an accessible point such as on the dash 2 of the vehicle, for manipulation by the foot of the operator, said rod being suitably insulated to prevent likelihood of the operator 95 sustaining a shock.

The use and operation of this invention will be clearly understood from the foregoing description and by reference to the 100 drawing. When it is desired to ignite the gas at one or more of the burners the main valve 11 is opened so as to distribute the gas through the respective conduits to the lamps and the operator pushes forwardly the rod 105 16 so as to throw the switch 13 normally con-

necting at 17 and 18 so as to make contact with the terminal 19 of the conductor 14 whereby the current momentarily passes to the electrodes at each of the lamps igniting the gas. Release of the operator's foot causes the rod 16 to return to its former position under the actuation of a spring 20 to close the circuit again to the engine spark plug, and the breaking of the supply of current to such plug for ignition as described will not impair the running action of the motor to any appreciable extent.

As will be obvious, the burners may be operated independently by manipulation of the auxiliary valves 12 and 12' or they may be ignited in succession by the proper adjustment of the distributor valves in a manner well known to those skilled in the art to which this invention refers. Each of the burners is suitably supplied with a supporting bracket or clamping member 21 for holding the electrodes 15' in proper position at the burner and it will be obvious that changes may readily be made in the exact details of construction without departing from the spirit of the invention and within the scope of the claim hereto appended, such changes comprehending the provision of additional conduits for conducting gas to other lamps than those hereinbefore specified and which may be included in the gas circuit, each of the additional lamps being, of course, also included in the electric circuit.

Copies of this patent may be obtained for five cents each, by addressing the "Commissioner of Patents, Washington, D. C."

Having thus described the invention, what is claimed as new is:

In igniting apparatus of the class described, the combination with engine cylinders adapted for use on an automobile, and an automobile dash adjacent the cylinders, the cylinders having spark plugs and electric circuits therefor, of an insulating block fixed adjacent one of the spark plugs, a switch pivotally connected at one end to the block and arranged in the circuit of the last named spark plug, an ignition circuit including a portion of the last named spark plug circuit and having the conductor connected with the insulating block adjacent the conductor of the last named spark plug circuit, the switch being adapted to be moved on its pivot for breaking the spark plug circuit and into contact with said conductor for making the ignition circuit, a rod pivoted to the switch at an intermediate point and extending through the dash, and elastic means pressing the rod in a direction for maintaining the switch on closed circuit in the last named spark plug circuit and for returning the switch thereto after being shifted to the ignition circuit closing position by longitudinal thrust of said rod.

In testimony whereof I affix my signature in presence of two witnesses.

CHARLES ERNEST SMITH.
